UNITED STATES PATENT OFFICE.

FREDERICK G. KEYES, OF EAST ORANGE, NEW JERSEY, ASSIGNOR TO COOPER HEWITT ELECTRIC COMPANY, OF HOBOKEN, NEW JERSEY, A CORPORATION OF NEW JERSEY.

TERMINAL FOR ELECTRIC APPARATUS.

1,197,830.

Specification of Letters Patent. Patented Sept. 12, 1916.

Application filed June 16, 1914. Serial No. 845,261.

To all whom it may concern:

Be it known that I, FREDERICK G. KEYES, a citizen of the United States, and resident of East Orange, county of Essex, State of New Jersey, have invented certain new and useful Improvements in Terminals for Vapor Electric Apparatus, of which the following is a specification.

The invention herein disclosed is an improvement on the invention set forth in my Patent No. 1,079,352, issued November 25th, 1913. In the invention disclosed in said patent I employ a seal consisting of a metal tube, usually platinum, passing through a vitreous member sealed to the tube and leading to a chamber inside the main container, wherein I supply an absorbing material interposed between the interior of the container and a tube for preventing the impairment or destruction of the efficiency of the seal by gradually absorbing the vapor which may pass through into the absorbent material. In practice the functional life of such an absorbent material, provided proper precautions are used and even though it be of moderate extent, is in excess of the life of the vapor apparatus as a whole. The earlier disclosure took the form of granules or powder of some metal, such as copper, which amalgamates with the mercury with considerable readiness. By this amalgamation the copper powder or granules absorb the mercury vapor carried through from the interior of the container, and thus hinder the penetration of mercury vapor by arresting and absorbing the vapor which has already penetrated.

In the present invention I do not employ a powder or granules of copper for the reason that the same are liable to be too thick or to be blown into the lamp and amalgamate with the mercury used in the conducting process. It also appears that quartz or glass absorbs copper at high temperatures. I still make use, however, of the greater tendency of copper to absorb mercury in preference to platinum, but I supply the copper in the form of a rod welded to the iron of the leading-in cap or in the form of a spiral surrounding the portion of the platinum tube within the seal.

My invention is illustrated in the accompanying drawings in which—

Figures 1 and 2 are vertical sections of quartz lamp apparatus, each having the

principle of my invention applied thereto in a different way.

In the drawings, A is a tube of non-conducting material which forms part of the container into which current is to be introduced. By way of illustration I shall assume the container to be constructed of fused silica or quartz.

B is a thin metal tube, usually of platinum.

C is a vitreous member which is secured to the platinum tube B on the one hand and to the fused silica tube A on the other.

D is a lead passing through the tube B into the container tube A and sealed or otherwise secured to a metal cap-piece E which cap piece is secured to the tube B. The sealing of the cap-piece, tube and lead, is usually performed by a single operation.

The part D which I have described as the lead is really made up of two parts, already described, the lower part being of copper and the upper part G of iron, the two being secured together by solder or otherwise at the point H.

Between the copper rod or wire constituting what I have called the lead, and the inner wall of the container tube, I may insert a barrier of pulverulent material, such as ferric oxide, the interstices between the particles of which are so minute that even mercury vapor penetrates with extreme difficulty and slowness, or I may use a loosely fritted material, the minute particles of which adjust themselves as the temperature changes, or, I may employ plastic resin, either natural or artificial, which at high temperatures possesses just enough plasticity to yield to the volume changes imposed by thermal changes of the various parts. It will be recognized that the barrier material must adapt itself to the shape and dimensions of the materials with which it comes in contact without exerting a dangerous or deleterious pressure thereon. The barrier material is here shown at I. This material is held in place by a diaphragm J which may be of a material which is introduced in the form of a powder or paste and which is readily baked into a more or less coherent mass. There is an opening in the diaphragm through which the rod G passes and this opening should be slightly larger than the rod so that it is not engaged thereby but slips therein with great freedom.

Under the conditions described above it will be understood that any mercury vapor which passes through the diaphragm in the operation of the apparatus will meet with the mechanical or physical obstruction of the pulverulent material I and be arrested thereby, while that part of it which actually penetrates will attack the copper lead D and amalgamate therewith. Thus the functions of the apparatus disclosed in my Patent No. 1,079,352, are performed by the structure herein described and the inconveniences arising from the use of the patented device are avoided.

The general features of the apparatus shown in Fig. 2 are the same as those in Fig. 1, but the lead consists wholly of iron

and the copper is arranged in the form of a spiral generally outside the platinum tube B.

I claim as my invention:

In a vapor electric apparatus, a container, a tubular platinum lead sealed through the wall of the container, a rod of solid conducting material inside the platinum lead, and a rod of copper arranged spirally around the said solid rod.

Signed at New York in the county of New York and State of New York this 11th day of June, A. D. 1914.

FREDERICK G. KEYES.
